BY Victor J. Evans

ATTORNEY

W. M. Evans

WITNESS:

UNITED STATES PATENT OFFICE.

EDWARD A. FOSTER, OF IBEX, VIA ALBANY, TEXAS.

SPRING.

Application filed July 26, 1924. Serial No. 728,397.

To all whom it may concern:

Be it known that I, EDWARD A. FOSTER, a citizen of the United States, residing at Ibex, via Albany, in the county of Shackelford and State of Texas, have invented new and useful Improvements in Springs, of which the following is a specification.

My present invention has reference to springs for vehicles, especially for automobiles.

My object is to construct a full elliptical, semi-elliptical or quarter-elliptical spring whose leaves are made up each of a plurality of bars connected together in such a manner as to hold all of the leaves in proper alignment and of such construction and arrangement as to not only absorb the vertical shocks to which the body of the vehicle is subjected, but to likewise absorb shocks delivered against either side of the spring.

Another object is the production of a vehicle spring whose leaves are made up each of a plurality of bars, the end bars of one series being of a greater thickness than the end bars of the adjacent series, whereby the bars of the different series have the joints therebetween broken, and also wherein means comprising clips of a novel construction are employed for holding all of the leaves in proper alignment.

A still further object is the production of a vehicle spring whose leaves are made up of bars and which, at the center thereof, are bent outwardly at opposite angles to receive therebetween substantially diamond-shaped spacer blocks through which the tie bolt passes, so that the leaves at the center thereof will not be weakened by forming openings therethrough.

A still further object is the production of a vehicle spring whose leaves are made up of bars, the series of bars constituting the separate leaves are so arranged as to break the joints therebetween provided by the confronting bars, and likewise wherein the outer bars of the several leaves are coiled or rounded upon themselves to provide eyes received in clips of a novel construction and through which the securing bolts pass.

With the above broadly stated objects in view and others which will appear as the nature of the invention is better understood, reference is to be had to the drawings which

accompany and which form part of this application.

55

In the drawings:—

Figure 1 is a front elevation of an automobile provided with the improvement.

Figure 2 is a side elevation of a semi-elliptical spring in accordance with this invention, the axle to which it is connected being in section.

Figure 3 is a top plan view thereof.

Figure 4 is a bottom plan view thereof.

Figure 5 is a central transverse sectional view through the spring.

Figure 6 is a sectional view on the line 6—6 of Figure 2.

Figure 7 is a sectional view on the line 7—7 of Figure 6.

Figure 8 is a perspective view of one of the clips.

Figure 9 is a similar view of a plurality of superimposed spacer blocks.

Figure 10 is a perspective view looking toward the end of one of the spring leaves.

75

In the drawings, the numeral 1 designates the side bars in an automobile chassis, or the sills in any other vehicle body. The axle for the vehicle is indicated by the numeral 2, and a semi-elliptical spring, in accordance with this invention, broadly by the numeral 3. As disclosed by the several figures of the drawings, my improved spring 3 has its leaves constructed of any desired number of spring metal bars arranged in superimposed relation. The alternating side bars in the leaves of all of the series, are of a less thickness than the remaining bars. These reduced bars are indicated for distinction by the numeral 4, and the thicker bars by the numeral 5. By providing the thinner bars 4, it will be noted that the vertical joints provided by the abutting bars in the different series of leaves are broken, that is, the joints between the lower bars are disposed centrally between the next superimposed series of bars. This adds to the spring as a whole, and likewise tends to hold the bars of the different leaves properly positioned with respect to each other.

All of the bars, at the center thereof, are bent outwardly at opposite angles, providing at the center thereof substantially V-shaped spaces, and in these spaces there are placed 105 V-shaped spacer blocks 6, the said blocks be-

ing, of course, disposed in staggered relation with respect to each other, but all of which being provided with openings that align, and through these aligning openings there 5 is passed the tie bolt 7.

To the opposite sides of the tie bolt 7 the springs are engaged by the usual U bolts 8 that pass through the flanges of the axle 2 and have their ends engaged by the usual 10 nuts.

The short leaf of the spring that rests directly on the axle is indicated by the numeral 9 and is in the nature of a solid plate, while the side rods of the remaining 15 leaves have their ends rounded upon themselves to provide eyes 10. All of the eyes, except the eyes on the upper leaf are extended downwardly and are received next to ears 11 formed on the sides 12 of clips 20 13. The connecting elements between the sides of the clips are indicated by the numeral 14, the same being disposed adjacent to the ears 11 and being in spaced relation so that the eyes 10 of the spring 25 leaves may pass therebetween. The ears 11 have openings to align with the openings in the eyes and through these openings there are passed the usual bolts 15 engaged by nuts. The sides 12, adjacent to their upper 30 edges are also provided with aligning openings through which are passed bolts 16 engaged by the usual nuts. Of course, the clips vary in lengths so that the bolts 15 and 16 will contact with both the upper and 35 lower series of the spring leaves.

For distinction, the upturned eyes on the ends of the upper spring leaf are indicated by the numeral 17. These eyes are larger than the eyes 10, and receive therethrough 40 bronze bushings 18 that form the cores of steel tubes 19. Passing through the bronze bearing on the outer end of the spring and through openings in the outer end of the side bars 1 of the vehicle frame there are 45 the usual bolts 20. The side bars have pivotally secured thereto depending shackles 21 provided with the usual eyes or openings, and passing through the bronze bushings on the inner end of the spring and through 50 the shackles 21 there are the usual bolts 22. Of course, these bolts are engaged by nuts.

With my improved spring construction, a uniform atomic metal structure is attained with a material increase of the frictional or 55 braking action between the several leaves constituting the spring. The spring construction not only absorbs the shocks and jars imparted to spring leaves of the usual formation, but likewise absorbs, by yielding, 60 transverse torsional or racking strains without liability of breakage or fracture to the bars constituting the spring. In this connection it will be apparent that should one of the bars break, the same may be readily 65 replaced without substituting an entirely

new leaf therefor, and it is believed that the foregoing description, when taken in connection with the drawings will fully set forth the construction and advantages of my improvement to those skilled in the art 70 to which such inventions relate. I consider it necessary to add, however, that the improvement is not to be restricted to the structural features herein set forth, but is limited only by the scope of the appended 75 claims.

Having described the invention, I claim:—

1. A vehicle spring composed of a series of superimposed leaves, each leaf being formed of a series of bars placed side by side and the bars of each leaf being disposed centrally with respect to the meeting sides of the bars therebelow. 80

2. A vehicle spring composed of a series of superimposed leaves, each leaf being formed of a series of bars and the alternating outer bars on the sides of the leaves being of a less thickness than the remaining bars, for the purpose set forth. 85

3. A vehicle spring composed of a series of superimposed leaves, each leaf being formed of a series of bars and the alternating outer bars on the sides of the leaves being of a less thickness than the remaining bars, and the ends of the outer bars of each 95 leaf formed with an eye, for the purpose set forth.

4. A vehicle spring composed of a series of superimposed leaves, each leaf being formed of a series of bars and the alternating outer bars on the sides of the leaves being of a less thickness than the remaining bars, the ends of the outer bars of each leaf formed with an eye, clips having an open bottom receiving the ends of all but 100 the upper leaf, binding means passing through the clips and eyes and other binding means passing through the clips and overlying the top leaf of the spring. 105

5. A vehicle spring composed of a series 110 of superimposed leaves, each leaf being formed of a series of bars, each bar of each series being of an equal length, and the alternating outer bars on the sides of the leaves being of a less thickness than the remaining bars, and the ends of the outer bars of each leaf formed with an eye, for the purpose set forth. 115

6. A vehicle spring composed of a series of superimposed leaves, each leaf being 120 formed of a series of bars and the alternating outer bars on the sides of the leaves being of a less thickness than the remaining bars, and means surrounding and connecting the leaves for holding the bars constituting the 125 same in frictional engagement with each other.

In testimony whereof I affix my signature.

EDWARD A. FOSTER.
